DESIGN FOR A FILING CABINET OR SIMILAR ARTICLE

Charles Wykel and Peter Michel, Glendale,
Long Island, N. Y.

Application January 20, 1940, Serial No. 89,600

Term of patent 14 years

To all whom it may concern:

Be it known that we, Charles Wykel and Peter Michel, citizens of the United States of America, residing at Glendale, Long Island, in the county of Queens and State of New York, have invented a new, original, and ornamental Design for a Filing Cabinet or Similar Article, of which the following is a specification, reference being had to the accompanying drawing, forming a part thereof.

We claim:

The ornamental design for a filing cabinet or similar article, as shown.

CHARLES WYKEL.
PETER MICHEL.
